CLAIM

We claim the ornamental design for a beverage cartridge and press assembly, as shown and described.

DESCRIPTION

FIG. 1 is a perspective view of a beverage cartridge and press assembly showing our new design with the tap in closed position;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of a beverage cartridge and press assembly showing our new design with the tap in open position;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

The broken lines in the drawing depict portions of the beverage cartridge and press assembly that form no part of the claimed design.
